UNITED STATES PATENT OFFICE.

JAMES M. WORKMAN, OF GREENVILLE, SOUTH CAROLINA.

CLOSURE-OPERATOR.

1,356,803.

Specification of Letters Patent. Patented Oct. 26, 1920.

Application filed January 4, 1918. Serial No. 210,343.

To all whom it may concern:

Be it known that I, JAMES M. WORKMAN, a citizen of the United States, and resident of Greenville, county of Greenville, and 5 State of South Carolina, have invented an Improvement in Closure-Operators, of which the following is a specification.

The object of my invention is to provide an effective means for operating pivoted or 10 hinged window sashes, more especially for factory buildings and large public halls or auditoriums, the construction being so designed as to enable the sash to be positioned to various degrees of opening and held in 15 such positions, but at all times capable by easy manipulation by an attendant, to change the angles of or close the sash.

In general, my invention comprehends a pivoted window sash to which is hinged an 20 operating bar associated with operating chains or cables by which the window sash may be tilted from a closed position to any angle of opening, the said operating mechanism being provided with means for holding 25 the sash in position when opened to the desired degree, all of which is more fully described hereinafter and specially pointed out in the claims.

My improvements will be better understood 30 by reference to the accompanying drawings, in which: Figure 1 is a vertical section of a portion of a window frame and pivoted sash showing my improvements applied thereto when the sash is held in open 35 position; Fig. 2 is a similar view but with the operative parts manipulated to permit the sash to be closed; Fig. 3 is a vertical sectional view illustrating the window sash in closed position; Fig. 4 is a front view of 40 the bracket and attached parts in Fig. 1 with part in section; Fig. 5 is a vertical section corresponding to Fig. 3 but showing a modification of my invention; and Fig. 6 is an elevation of the specially constructed sheave 45 shown in Fig. 5.

2 is the fixed member of the window sash and 3 indicates the usual hinged or pivoted sash member thereof which in many cases is of considerable size, constituting approximately 50 one-half of the whole window. 4 is an operating bar which is hinged to the pivoted sash 3 at 5 and the said hinged end of the bar 4 is laterally curved as at 6, as indicated in Fig. 3, to enable it to bridge over 55 the operative mechanism when the window sash 3 is closed. This bar 4 is provided

with a plurality of lugs or teeth 7, spaced at intervals along its length and also has its lower or free end turned at an angle as indicated at 8 for connection with the end of the 60 operating chain or cable 18, employed in opening or controlling the closing of the sash. An operating chain or cable 17, for closing the sash, is connected to the bar 4 adjacent to its hinge point 5 with the sash 3, so 65 that when a pull upon the chain or cable 17 is given, the power is applied to the sash 3 so close to the hinge 5 of the bar 4 that the pull in effect is substantially upon the sash. The chains or cables 17 and 18 pass about 70 suitable guide pulleys 16 and depend to within easy reach of an operator and desirably connect into a loop, as at 19. It will be understood that if the parts are in the relation illustrated in Fig. 3, a pull upon the 75 cable 18 would tend to raise the bar 4 and exert a lateral thrust at the hinge point 5, which would open the sash allowing it to assume a position as indicated in Figs. 1 and 2. Means for retaining the bar 4 in 80 the position assumed are provided and comprise a cross bar 10 which, at its lower part engages the notches 22 in the bracket and is provided at its ends with upwardly extending arms 10^a arranged upon the outer 85 sides of the guard 9^a of the bracket and is locked in position at the top by a cross pin 23 of fusible metal. This fusible pin 23 holds the bar 10 down in engagement with the notches 22 of the bracket to prevent its 90 shifting under normal conditions. The lugs or teeth 7 of the actuating bar 4 are inclined at the forward ends so as to slide over this cross bar 10 and engage it in such a manner as to lock the said bar 4 against a 95 return movement. To provide for the disengagement of the bar 4 with the cross bar 10, I employ a lever 12 which is hinged at 13 to the bracket 9, said lever having a short arm 14 projecting horizontally above the 100 grooved wheels 16 and under the bar 4, and further having a downwardly extending arm carrying a grooved pulley 15 over which the downwardly extending portion of the chain 17 passes. It will now be understood, that if the lower part of the chain 17 be pulled, the lever 12 will be oscillated, as clearly indicated in Fig. 2; and the result of this is, that the arm 14 forces the bar 4 upward within the guard 9^a of the 105 bracket, so that the lugs 7 thereof clear cross bar 10, and thereafter the manipulations of

110

the two chains or cables 17 and 18 permit the bar 4 to move backward to close the sash 3 to any degree desired. By manipulating the chains or cables 17 and 18, the sash 3 5 may be moved toward and into a closed position upon the fixed sash 2. In opening the window sash there will be no necessity of any pull upon the chain or cable 17, as the pull upon the cable 18 moves the bar 4 10 freely over the cross bar 10 to the position desired.

When the sash is fully closed (Fig. 3) and the bar 4 hangs in a vertical position, any attempt to open the sash 3 by directly 15 pulling upon the same would be resisted with an enormous leverage produced by the bar 4 which is an effectual lock against any wind pressures upon the sash, but the operating bar also has a lug 20 which engages 20 the cross bar 10 to positively lock the sash against unlawful opening from the outside.

In case of fire, it is desirable that the window sash 3 should automatically close and this action is provided by having the cross 25 bar 10 connected in place upon the bracket 9 and its guard 9^a by fusible pin 23 which fuses under the increased temperature and permits the lug of bar 4 to rock the locking bar 10 out of position and cause the bar 4 to 30 move backward and downward and the window sash 3 to move to a closed position by gravity. This cross bar 10 may be of any desired shape and the fusible connection or joint at the upper end may be of any degree 35 of strength to suit the requirements in any particular window construction. It will be understood that by placing the fusible pin 23 high up above the bar 4, it is in position to receive the effect of the heat in case of fire, 40 to the best advantage, and at the same time is protected from injury from the moving parts of the apparatus. It is also pointed out that the locking pin 23 is so far from the bar 10 and its engaging or retaining 45 notches 22 that a relatively light pin will sustain the strain and hence be more easily fusible. The fusible connection between the arms 10^a and the bracket 9 may be made in other ways if so desired without departing 50 from the essential requirements of the invention.

In the modification shown in Fig. 5, the bracket 9 is provided with a specially constructed grooved sheave 16^a which has two 55 main grooved portions 16^b and 16^c, the former of which is provided with a lateral grooved portion 16^e which continues in a further circumferential groove 16^d. The grooves 16^e and 16^d are relatively shallower 60 than the grooves 16^b and 16^c and operate to provide a cam action upon the chain or cable 18 by jamming it against the wall 24 of the bracket 9 whenever it is desired to lock the bar 4^a from a return movement. The chain 65 17 for closing the sash is guided in the

groove 16^e of the sheave 16^a whereas the cable 18 for lifting the bar 4^a and opening the sash 3 is guided in the groove 16^b of the sheave. The end 10^b of the bracket may be shaped to prevent disengagement of the 70 chains or cables from the sheave. In manipulating the chain 18 to open the sash 3 and hold the bar 4^a to maintain the open position of the sash, the following operation is required: The chain 75 18 is pulled downward and when the sash 3 is opened to the desired distance, the said chain is pulled laterally over the sheave so that it enters the groove 16^e and into the cam groove 16^d, then upon slightly relieving the 80 pull upon the chain it will be carried upward and jammed between the abutment 24 and the shallow grooved portion 16^d of the sheave, thereby retaining the bar 4^a and the sash in their open positions. To close the 85 sash the chain 18 is pulled until it runs back into the groove 16^b, and thereafter it is payed upward and if desired, assisted by a downward pull upon the chain 17 until the parts arrive at the positions indicated in 90 Fig. 5. As shown in this figure, there is a lug 20 upon the curved portion 6 of the bar 4^a, said lug being in horizontal alinement with a lug 21 on the bracket 9. The result of this is, that should an attempt be made to 95 pull the window sash outward, the lug 20 will engage the lug 21, which will thereby act as a lock to prevent such opening. It is manifest that lugs of this character 20 and 21 may be employed on the constructions of 100 Figs. 1 to 3 equally well, if so desired.

While I have described the transverse bar 10 as being secured in place by fusible pin, it is to be understood that I do not restrict myself in that respect, as said bar may be 105 firmly secured to or made integral with the bracket 9.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood 110 that I do not restrict myself to the details, as the same are susceptible of modification in various particulars without departing from the spirit or scope of the invention.

Having now described my invention, what 120 I claim as new and desire to secure by Letters Patent, is:—

1. In a closure operator, the combination of a fixed frame adapted to close by gravity, and a movable closure, with an operating 125 bar hinged to the movable closure and having along its length a plurality of ratchet teeth, a bracket secured to the fixed frame and having an abutment with which the ratchet teeth of the operating bar automati- 130

cally engage for holding the closure in open position, guide pulleys journaled on fixed axes on the bracket, two chains or cables respectively connected to the operating bar at 5 its opposite ends and passing about the guide pulleys to provide downwardly extending portions by which a pull upon the respective chains or cables may open or control the closing of the movable closure, and 10 means independent of the movable closure and pulleys and their support to disengage the teeth of the hinged operating bar from the abutment of the bracket controlled by the chain or cable leading to the end of the 15 bar which is hinged to the movable closure.

2. The combination of a fixed frame adapted to close by gravity, with a movable closure, and means for operating the movable closure consisting of an operating bar 20 having its upper end laterally curved and hinged to the movable closure and provided with ratchet teeth inclined on one side, said bar hanging vertically and acting as a lock when the movable closure is closed, a bracket 25 secured to the fixed frame and having an abutment with which the teeth may engage in one direction only to hold the movable closure in open position, guiding means on the bracket close to the abutment, a chain or 30 cable guided about the guiding means and having one end connected with the free or inner end of the operating bar and the other end extending downward from the guide, and hand manipulated means for raising the 35 operating bar out of engagement with the abutment to permit the closing of the movable closure by gravity.

3. The combination of a fixed frame, with a movable closure, and means for operating the movable closure consisting of an operating bar hinged to the movable closure and provided with ratchet teeth, a bracket secured to the fixed frame and having a detachable cross bar with which 45 the teeth automatically engage to hold the movable closure in open position, said bar secured in place by being releasably held in position, a guide on the bracket, a chain or cable guided about the guide and having one end connected with the free end 50 of the operating bar and the other end extending downward from the guide, and hand manipulated means for raising the operating bar out of engagement with the cross bar and to permit the closing of the movable closure by gravity.

4. The combination of a fixed frame, with a movable closure, and means for operating the movable closure consisting of an operating bar hinged to the movable closure and provided with ratchet teeth, a bracket secured to the fixed frame and having an abutment with which the teeth engage to hold the movable closure in open position, 60 and freely movable over the abutment in

opening the frame, a guide held in fixed relation to the bracket, a chain or cable guided about the guide and having one end connected with the free end of the operating bar and the other end extending downward from the guide, pivoted means independent of the guide for raising the operating bar out of engagement with the abutment and to permit the closing of the movable closure by gravity, and a second chain or cable extending from the movable closure and guided about the guide on the bracket and adapted to operate the pivoted disengaging means.

5. The combination of a fixed window frame, and a movable closure adapted to close by gravity, with an operating bar hinged to the movable closure for moving it and provided with teeth along its length, a bracket secured to the fixed frame and having means to engage the teeth of the operating bar for holding the movable closure in any open position desired and freely movable over the abutment in opening the closure, a guide held in fixed relation to the bracket, a chain or cable having one end connected to the free end of the operating bar and guided about the fixed guide in one direction and having its other end connected to the bar adjacent to the window closure and guided about the guide in the other direction whereby the operating bar may be manipulated in opening or closing the movable closure, and a pivoted lever independent of the guide on the bracket having an arm for raising the operating bar to disengage its teeth from the engaging portion of the bracket said lever actuated by the portion of the chain leading from the outer end of the bar.

6. The combination of a fixed window frame, and a movable closure adapted to close by gravity, with an operating bar hinged to the movable closure for moving it and provided with teeth along its length, a bracket secured to the fixed frame, an abutment engaging the bracket and shaped to engage the teeth for holding the movable closure in any open position desired and freely movable over the abutment in opening the closure, a fusible bolt for locking the abutment in fixed relation to the bracket, a guiding means on the bracket, a chain or cable portion extending from the free end of the operating bar and guided in one direction about the guiding means, a chain or cable portion extending from the closure end of the operating bar and guided about the guiding means in the other direction, a pivoted lever having an arm for raising the operating bar to disengage its teeth from the engaging portion of the bracket and operable by the chain or cable portion leading from closure end of the bar.

7. The combination of a fixed window

frame, and a movable closure adapted to close by gravity, with operating means for the movable closure consisting of a long operating bar having teeth along its length and said bar laterally curved at its upper end and hinged thereat to the movable closure, a bracket secured to the fixed frame and immediately under the laterally curved portion of the bar when the closure is in closed position and having an abutment adapted for engagement of the teeth, rotary guiding means journaled in the bracket, cables extending from opposite ends of the operating bar and guided in opposite directions about the rotary guiding means, and hand controlled means for actuating the operating bar to release it from engagement of the abutment.

8. The combination of a fixed window frame, and a movable closure adapted to close by gravity, with operating means for the movable closure consisting of a long operating bar hinged to the movable closure and provided with ratchet teeth along its length, a bracket secured to the fixed frame and forming a guide for the bar said bracket provided with notched portions on its side most distant from the fixed frame, a U shaped abutment frame extending across the bracket for engaging the teeth of the bar and said abutment frame having portions at

its lower part engaging the notched portions of the bracket, said abutment frame having its upper portion releasably held to the bracket, chains for operating the bar for opening or closing the movable closure, and hand controlled means for disengaging the operating bar from the abutment when closing the movable closure.

9. The combination of a fixed window frame, and a movable closure adapted to close by gravity with an operating bar hinged to the movable closure and provided with teeth along its length, with means to shift the operating bar for opening and closing the closure, an abutment device for engaging the teeth of the bar for holding the movable closure in open position, said abutment device comprising a hinged part detachably connected at its lower end in relation to the fixed frame, and releasably connected at its upper end for normally holding the abutment device against release but which under the application of heat permits the abutment device to oscillate and release the operating bar.

In testimony of which invention, I hereunto set my hand.

JAMES M. WORKMAN.
